STRIPPER MECHANISM FOR CONVEYERS

Charles A. Davidson, Pottstown, Pa.

Application April 21, 1945, Serial No. 589,665

4 Claims. (Cl. 198—230)

This invention has reference to conveyers in general while it relates more particularly to the species of conveyer useful in furnaces serviceable for the heat-treatment of metal objects or things for tempering or hardening. Incidental to the high temperature in which such conveyers customarily operate the metal objects or things being treated frequently cling or burn fast to the supporting surface of the conveyer with the result that, as said articles or things arrive at the discharge or unloading end of the active flight of such conveyer they are liable to be transported therebeyond with resultant destruction and waste of valuable material due to over-heating, burning and so forth.

The primary object of this invention is to effectively remove any possibility for the passage beyond the discharge end of the conveyer, as above indicated, of any object or thing clinging to such conveyer.

Another object is the provision of an adjustable stripper means whereby articles or things clinging to, or otherwise adhered on, the active flight of a heat-treating furnace conveyer are positively precipitated from or forcibly removed, as they reach the discharge end of such conveyer.

A further object is to furnish a conveyer belt-scaper or cleaner which is automatic in action and the various component parts whereof are easily removable and replaceable when necessary or required.

While the foregoing definitions are indicative, in a general way, of the aims of this invention, other objects with ancillary advantages will be evident to those skilled in the art upon a full understanding of the construction, arrangement and operation of the means hereinafter fully disclosed; but it will also be appreciated that the invention is susceptible of other embodiment or structurally modified forms coming equally within the terms and scope of the concluding claims.

In the drawings:

Fig. 1 is a part side, and part sectional, elevation of a fragmentary portion of a heat-treating furnace including the novel conveyer-stripping means of this invention; and,

Fig. 2 is a plan section of the same taken approximately as indicated by the angled arrows II—II in Fig. 1.

In describing the form of this invention exemplified by the drawings above identified, specific terms will be employed for the sake of clarity, but it is to be understood the scope of said invention is not thereby limited; each said term being intended to embrace all equivalents

which perform the same function for an analogous purpose.

Referring more in detail to the drawings, a fragmentary portion of a conventional heat-treating furnace is comprehensively designated by the reference character 3, said portion conveniently being the discharge end thereof for better illustration of the stripper-cleaner means of this invention. A fragmentary part of the conveyer 10 is designated by the numeral 4, and said conveyer is, conveniently, of the inter-engaging slat type so as to present a flat carrying surface, for progression thereon of the objects or things, such as different sized ball or roller races, spline sleeves and so forth, as typically indicated by the reference characters 5, 6, Fig. 1, for example only; while said conveyer is, preferably, provided with flanges 7 to prevent said castings from falling thereof at the sides. The conveyer 4 is conveniently, although not essentially, trained about appropriate spiked drums or spaced gears 8, fast on the drive-shaft 9 and journaled in bearings 10 outside the furnace 3; while 11, comprehensively marks the chute down which the castings 5, 6 fall into a suitable quenching receptacle or tank, not shown, all of said parts having been briefly referred to in order to provide a proper background for clarification of this invention.

Journaled in stationary bearings 12 affixed to the outer walls of the furnace 3, and in spaced relation with respect to the conveyer drive-shaft 9, is a pivot-shaft 13 on which is splined or suitably secured a tubular member 14 embodying radial arms 15 preferably integral with a stripping or scraper blade 16, arranged for coaction with the outer running or discharge end of the conveyer 4 and below the level of the axis of rotation of the drive-shaft 9, for a purpose hereinafter explained.

Fastened on each outer projecting end of the pivot-shaft 13, as by key means 17, Fig. 1, is the sleeve-like or hub-end 18 of a lever-arm 19; while said hub-end 18 embodies a tooth-projection 20 arranged for abutment below a lateral stop-lug 21 integral with the adjoining stationary bearing 12. Thus it will be seen that the respective lever-arms 19 are limited as regards oscillatory movement to the left hand, as best understood from Fig. 1, whereas they can rock to the right hand for reasons later explained. Attention is directed to the stripping or scraper blade 16, the same being of somewhat wedge-shape in cross-section with the active edge 22 upwardly directed relative to the common plane of the radial arms 15 as clearly shown in Fig. 1; while it is to be

further noted, said active edge 22, normally, is located in close juxtaposition to the path of travel of the conveyer supporting surface. Or, incident to abutment of the tooth-projection 20 against the underside of the stationary stop 21, the stripping or scraper blade 16 is positively prevented from actual contact with the active face of the conveyer; so that ordinarily, as said conveyer travels in the direction of the associated arrow shown in Fig. 1, the non-adhered smaller articles 5—or the larger objects 6—will be easily moved from the conveyer surface and roll or slide down, the inclined face 23 of the blade 16, said face being normally positioned at an angle, preferably of slightly less than forty-five degrees in respect to the vertical, and over the upper rounded butt-edge 24 thereof, intermediate the radial arms 15 into the chute 11 and drop into the quenching, tempering or annealing receptacle therebelow.

In order to positively ensure that any adhered or burnt-on object or objects, which cling to the conveyer 4, shall be stripped from said conveyer as they reach the active edge 22 of the blade 16; the respective upper end of each lever-arm 19 is forked at 25 for pivotal connection by suitable means 26, to the eyed end 27 of an associated pull-rod 28, in turn engaged through an appropriate guide bracket 29 rigidly attached to the furnace wall. Each such pull-rod 29 is fitted with a recoil spring 30 and associated lockable-adjustor means 31 on its threaded outer portion 32 whereby the reactive influence of said spring may be varied as desired. Now, it will be apparent that when a heavier object or objects 6, which are more liable to be adhered to or cling on the face of the conveyor 4, reach the active edge 22, said edge will serve to shear the object or objects 6 therefrom while the shearing action will be controlled by the degree of resistance applied to the spring 30 by the adjustor means 31, as readily understood by those acquainted with the art. In other words, removal of the object or objects 6 will be effectively carried out by what may be conveniently termed as a combination scraper-cleaning force exerted on the conveyer end, with the result that said conveyer is freed of any adhering impedimenta otherwise tending to obstruct smooth operation of the stripper means described.

It is also obvious that as a heavier object or objects 6 is removed from the conveyer 4 by the stripper or scraper blade 16, in opposition to the influence of the spring 30, that said blade will be rocked downwardly, as indicated by dot-and-dash line showing, while the face 23 of the blade 16 is still maintained at an inclination sufficient to ensure that the released object or objects 6 will slide downwardly therefrom over the rounded butt-edge 24 and gravitate down the chute 11

into the tempering or annealing receptacle therebelow as aforesaid; or it may be precipitated over the active edge 22 as conventionally shown, by the dot-and-dash indication 6, towards the right side of said chute.

From the foregoing it will be clear that the conveyer 4 may be of any convenient type, and that it can be chain or link driven where said conveyer is guided on rails or the like, to maintain the active flight flat, through the furnace 3; and furthermore it will also be self-evident that my novel stripper means fully justifies all of the objects set forth in the prefatory paragraphs of this specification.

15 Having thus described my invention, I claim:

1. Stripper mechanism for a heat-treating furnace conveyer comprising a pivotal-shaft, journaled in spaced relation to the discharge end of said conveyer; radial arms projecting from 20 said shaft connected at their free ends by a scraper-blade of suitable cross section to provide an active edge for disposition in close juxtaposition across the conveyer discharge end; a lever arm on each outer end of the pivotal-shaft and 25 having a tooth-projection; stationary stop means for abutment by the respective tooth-projections to limit movement of the scraper-blade in one direction; a pull-rod fulcrumed to the free end of each lever with an associated rigid guide 30 means; a recoil device on each pull-rod in engagement with the guide means at one end thereof; and an adjustor means on said pull-rod in engagement with the other end of the said recoil device, whereby the force of such recoil device 35 is variable to control the degree of pivotal movement of the scraper-blade, for the purpose specified.

2. The invention of claim 1 wherein the scraper-blade is of wedge-shape with the active edge upwardly inclined at an acute angle to the vertical; and wherein said blade has its upper butt edge rounded, for the purpose specified.

3. The invention of claim 1 wherein the pivotal-shaft for the scraper-blade is journaled in 45 bearings, mounted exteriorly of the furnace, and wherein each said bearing embodies a stop means in the form of a laterally projecting lug for abutment by the associated lever arm tooth-projection, for the purpose specified.

4. The invention of claim 1 wherein the guide means for each pull-rod is in the form of an apertured bracket rigidly secured to the outer face of the furnace wall; and wherein the recoil device consists of a coil spring in compression 55 on the associated pull-rod intermediate said bracket and a lockable adjustor means engaged on the screw-threaded outer end portion of said pull-rod, for the purpose specified.
